[57] CLAIM

The ornamental design for a combined automobile taillight lens and cover, as shown and described.

DESCRIPTION

FIG. 1 is a perspective view of a combined automobile taillight lens and cover showing the new design; FIG. 2 is a top plan view thereof on an enlarged scale; FIG. 3 is a bottom plan view thereof on an enlarged scale;

FIG. 4 is a right side view thereof on an enlarged scale; FIG. 5 is a front view thereof on an enlarged scale.

The taillight housing is shown in broken lines in FIGS. 2, 3 and 4 for illustrative purposes only.

FIG. 1

FIG. 2

FIG. 3

FIG. 4

FIG. 5
